UNITED STATES PATENT OFFICE.

EDWARD M. HEWLETT AND WILLIAM K. RANKIN, OF SCHENECTADY, NEW YORK, AS
SIGNORS TO GENERAL ELECTRIC COMPANY, A CORPORATION OF NEW YORK.

ELECTRIC SWITCH.

Application filed August 15, 1921. Serial No. 492,612.

This invention relates to electric switches in which the contacts are separable in an insulating fluid, and more particularly to those in which pressure created by the arc at the 5 opening of the switch is utilized to create a blast of oil which is directed into the path of the arc and serves to extinguish the same.

One of the objects of our invention is to provide an improved arc extinguishing 10 means of this character and according to one specific embodiment, we provide an outer vessel adapted to contain an insulating liquid and an inner pressure chamber adapted to contain and to be immersed in the insulating 15 liquid and formed with a stationary electrode at the bottom thereof which has a passage extending therethrough, which passage communicates with the space outside of the pressure chamber. The movable 20 electrode is positioned within this passage when the switch is closed and is withdrawn therefrom through the pressure chamber on the opening of the circuit. An arc is at first formed within the pressure chamber between 25 the stationary electrode and the movable electrode, which, however, is quickly transferred from the stationary electrode to an annular conducting member located within the pressure chamber and concentric with 30 the opening in the stationary electrode. The arrangement is such that the blast of oil, which is formed as a result of the pressure created by the arc, is forced across the path of the arc stream, as it passes between the 35 movable electrode and the annular conducting member, in a direction at approximately right angles thereto, and thence through the opening in the stationary electrode. The downward stream of oil through this opening 40 serves to protect the contact surface of the stationary electrode from the hot gases. The movable electrode extends through a passage in the top of the chamber and on the opening of the circuit is finally withdrawn from the chamber, leaving this passage 45 open. If, by any chance, the arc should persist until the movable electrode has been withdrawn through this passage, a second blast of oil is directed through this passage 50 into the arc stream. We provide special means by which the gases discharged from the pressure chamber shall be freed from liquid and cooled before they are discharged into the atmosphere.

55 A further object of our invention is to

provide a switch comprising an outer oil containing vessel, provided with a cover and wherein all of the switch structure (with the exception of the movable electrode), which is contained within the vessel, is supported 60 by and removable with the cover. This structure is entirely free from contact with the walls of the outer vessel, which latter is preferably grounded.

Other objects and advantages will appear 65 from the following description taken in connection with the accompanying drawing in which Fig. 1 represents in vertical section a switch embodying our invention and Fig. 2 is a fragmentary view of the lower portion 70 of Fig. 1 drawn to a larger scale. In the drawing 10 indicates an outer metallic tank or vessel adapted to be supported on a suitable truck 11. Vessel 10 is provided with a metallic cover 12 formed with openings 75 in which are seated insulators 13. Extending through these insulators and serving as one of the terminals of the switch are conducting rods 14. These rods constitute a supporting means of the compression chamber or vessel 15. This chamber comprises a top plate 16 of insulating material, such as wood, a metallic bottom plate 18 and a metallic cylindrical side wall 19. The rods 14 are secured to the bottom plate 18 by means 80 of nuts 20 which force said plate against the ends of sleeves 22 of insulating material surrounding the rods 14. The top plate 16 surrounds the rods 14 and both top and bottom plates are tightly clamped against the 85 side wall 19 by means of bolts 25, this forming a rigid structure adapted to withstand considerable internal pressure.

Secured to the lower portion of the plate 18 by means of the bolts 26 is a conducting 90 member 27 formed with a downwardly extending chamber or vessel 28 which is adapted to support the split contact pieces 29 of the stationary electrode 30. Leads 31 secured at one end to the contact pieces 29 and at the other to the conducting member 27 pass through suitable openings formed in the sides of the chamber 28 and serve as means for carrying current to the stationary electrode. Springs 32, surrounding the 100 split contact pieces 29, are adapted to press the latter into contact with the movable electrode 32 when the switch is in closed position. When in this position, the lower end of the movable electrode seats itself in an 105

opening 33 in the bottom of the chamber 15. Supported upon members 27 and in contact with the side of an opening 34 formed in the metallic plate 18 is an annular conducting member 35 formed with an arcing surface 36 arranged immediately above the contact surfaces of the pieces 29. Secured between the annular member 35 and the plate 18 is a ring-shaped insulator 37 arranged to extend some distance above the surface 36 to prevent the arc from leaping to the plate 18. For this purpose also, the plate 18 is covered with a sheet of insulation 40. A cylinder 41 composed of insulating material surrounds the chamber 15 to prevent any electrical discharge from the chamber to the outer vessel.

The movable electrode 32 passes through insulating bushings 43 and 44 secured respectively to the plate 16 and to the cover 12 and is arranged to be operated by any suitable mechanism not shown. Supported upon the plate 16 and surrounding the movable electrode is an insulating tube or cylinder 45 which is arranged to direct the material ejected upwardly through the insulator 43, when the electrode has been withdrawn therefrom, against the baffle 46. Baffle 46 is formed of insulating material and is supported by means of the conducting rods 14. Insulating sleeves 48 are interposed between the top of the baffle and the insulator 13 and other sleeves 49 interposed between the baffle 46 and the plate 16. Suitable openings 50 formed in the cover 12 permit the gases formed at the opening of the switch to escape.

It will be seen from the foregoing that upon the opening of the switch an arc will be formed between the movable electrode 32 and the contact pieces 29 which will be transferred to the annular conducting member 35. The pressure created within the chamber 15 will force a blast of oil across the arc stream and through the opening formed in the stationary electrode. Under the influence of this pressure, the oil surrounding the chamber 15 will rise within the vessel 10. The movable electrode 32, which is rapidly withdrawn from the chamber 15 through the cool body of oil therein contained, finally leaves the passage 51 formed in the insulator 43 and if at that time the arc has not been extinguished, a second blast of oil will be directed from the chamber up through this passage and into the path of the arc.

It will be noted that the vessel 10, rods 14 and attached structure are spaced from the walls of the outer vessel and insulated therefrom and are readily removable with the cover for inspection and repair.

It will be noted that in the form shown in Figs. 1 and 2 of the drawing the arc gases are discharged through the bottom opening 53 and through the openings formed in the

sides of the chamber 28. In certain cases to prevent injury to the contacts 29 it may be advisable to close the lower portion of the chamber 28 and to provide the opening therefrom at a point between contacts 29 and the annular conducting member 35.

What we claim as new and desire to secure by Letters Patent of the United States, is,—

1. In a switch, an outer vessel having a cover and adapted to contain an insulating liquid, an inner vessel adapted to contain and to be immersed in said liquid, a stationary electrode within said inner vessel, a movable electrode extending through said cover and separable from said stationary electrode to form an arc in said inner vessel and means for conducting current to said stationary electrode, said means passing through said cover and serving as a support for said inner vessel and stationary electrode.

2. In a switch, an outer metallic vessel having a cover and adapted to contain an insulating liquid, an inner vessel constructed to withstand internal pressure and adapted to be immersed in and to contain said liquid, a stationary electrode, a movable electrode separable from said stationary electrode to form an arc within said inner vessel, and means comprising a plurality of similar members extending through and insulated from said cover for supporting said inner vessel and stationary electrode free and insulated from the walls of said outer vessel.

3. In a switch, an outer vessel having a cover and adapted to contain an insulating liquid, an inner vessel constructed to withstand internal pressure and adapted to be immersed in and to contain said liquid, a stationary electrode, a movable electrode extending upwardly through said vessels and insulated therefrom, said movable electrode being separable from said stationary electrode to form an arc within said inner vessel, and means comprising a plurality of insulator bushings extending through said cover and conducting rods extending therethrough for supporting said inner vessel and stationary electrode free and insulated from the walls of said outer vessel.

4. In a switch, an outer metallic vessel adapted to contain an insulating liquid, a cover for said outer vessel, an inner vessel spaced from said cover and forming a compression chamber, said inner vessel being adapted to contain and to be immersed in said insulating liquid, a stationary electrode electrically connected to said inner vessel, a movable electrode insulated from said vessels, and separable from said stationary electrode to form an arc within said inner vessel, and conducting supports for said inner vessel and stationary electrode extending through and insulated from said cover.

5. In a switch, an outer metallic vessel

- adapted to contain an insulating liquid, a cover for said outer vessel, an inner vessel formed in part of conducting material and constructed to withstand internal pressure, 5 said inner vessel being adapted to contain and to be immersed in said insulating liquid, a stationary electrode electrically connected to the conducting portion of said inner vessel, a movable electrode insulated from 10 said vessels, and separable from said stationary electrode to form an arc within said inner vessel, insulator bushings mounted in said cover, and conducting rods extending through said bushings and in electrical connection with the conducting portion of said inner vessel, said rods supporting said inner vessel and stationary electrode free of and insulated from said outer vessel, and said inner vessel and stationary electrode being 15 removable with said cover.
6. In a switch, a vessel adapted to contain an insulating liquid, electrodes separable to form an arc within said vessel, one of said electrodes being supported by an end wall of 20 said vessel and being formed with an opening therethrough for receiving the other electrode to make contact therewith, said end wall having a passage therein communicating with the outer end of said opening in 25 the electrode, through which passage insulating liquid is discharged from said opening.
7. In a switch, a vessel adapted to contain an insulating liquid, electrodes separable to 30 form an arc within said vessel, one of said electrodes being supported by an end wall of said vessel and being formed with an opening therethrough to receive the other electrode to make contact therewith, said end 35 wall comprising an electrode retaining member provided with a passage therein communicating with the outer end of said opening in the electrode, through which passage insulating liquid is discharged from said 40 opening.
- 45 8. In a switch, an outer vessel adapted to contain an insulating fluid, a closed inner vessel adapted to be submerged in and to contain said insulating fluid, a stationary electrode within and supported by said inner vessel, a movable electrode adapted to co-operate therewith and to be withdrawn through the top of said inner vessel, a cover for said outer vessel and means depending from said cover for supporting said inner vessel.
9. In a switch, a vessel adapted to contain an insulating liquid, an electrode within said vessel, a second electrode within said vessel and separable from said first named electrode, and a conducting member in proximity to said first named electrode but separated therefrom by a space which communicates with the exterior of said vessel, the arrangement being such that upon separation of the electrodes an arc is formed within said vessel, which arc is transferred from said first named electrode to said conducting member, and insulating fluid under the influence of pressure created by said arc 70 is forced into the path of said arc and through said space.
10. An electric switch comprising a vessel adapted to contain an insulating fluid, a cover therefor, an inner vessel adapted to be 75 submerged in said insulating fluid, a stationary electrode carried at the bottom of said inner vessel, a movable electrode adapted to co-operate therewith to form an arc in said inner vessel and to be withdrawn 80 through the top thereof, a baffle interposed in the path of the material ejected by said arc when said movable electrode is withdrawn and means for removably supporting said inner vessel, said stationary electrode 85 and said baffle from said cover.

In witness whereof, we have hereunto set our hands this 12th day of August, 1921.

EDWARD M. HEWLETT.
WILLIAM K. RANKIN.
